UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 33,021, dated July 31, 1900.

Application filed October 5, 1899. Serial No. 732,728. Term of patent 14 years.

To all whom it may concern:

Be it known that I, JEREMIAH A. SCRIVEN, a citizen of the United States, residing in the borough of Manhattan, city, county, and State of New York, (whose post-office address is No. 18 East Fifteenth street,) have invented and produced a new and original Design for Bifurcated Nether Garments, of which the following is a specification.

10 The characteristic features of my design consist in elongated panels or insertions let into the garment and converging in the tubular members thereof to present substantially V-shaped insertions in each tubular member

15 of the garment.

In the accompanying drawing the figure represents a rear view of a bifurcated nether garment embodying my design.

A represents the body portion of a bifurcated nether garment, from which extend 20 tubular members B. Let into the garment are a series of insertions or panels a, which extend longitudinally from substantially the upper end of the garment to and beyond a point in each of the tubular members, (indicated at b,) where the insertions converge. The wales or ribs c of each of the insertions extend longitudinally thereof.

What I claim is—
The design for a bifurcated nether garment, 30 substantially as herein shown and described.

JEREMIAH A. SCRIVEN.
